UNITED STATES PATENT OFFICE.

MORTIMER S. BROWN, OF BROOKLYN, NEW YORK.

VEHICLE.

1,307,723.

Specification of Letters Patent. Patented June 24, 1919.

Application filed January 19, 1918. Serial No. 212,612.

To all whom it may concern:

Be it known that I, MORTIMER S. BROWN, a citizen of the United States, and resident of Brooklyn, in the county of Kings and State of New York, have invented certain new and useful Improvements in Vehicles, of which the following is a specification.

This invention relates to vehicles and especially to self-propelled passenger coaches, whether railway or what is commonly known as the omnibus and the object of the invention is to provide a light but substantial frame work capable of containing two tiers of seats within very limited space to provide for a maximum carrying capacity in a coach of the usual size. Other novel and useful details are also provided to economize in space and afford a compact and substantial construction, as will be more fully described in the following specification, set forth in the appended claims and illustrated in the accompanying drawings, wherein:

Figure 1 is a front view of the improved vehicle.

Fig. 2 is a cross sectional view of the same with the front platform and wall removed.

Fig. 3 is a cross sectional view through the coach and seats.

Fig. 4 is a cross section through a modified construction.

Fig. 5 is a side elevation slightly modified.

Fig. 6 is a longitudinal sectional view.

In populous cities where cars and coaches are run on those thoroughfares which are much frequented there are certain hours when the cars are crowded to excess and other times when the patronage is limited.

The tendency in the construction heretofore of these cars and coaches has been to provide an abundance of standing room and to neglect the comfort of the passengers as far as seating capacity is concerned.

The present invention is especially designed to seat all of the passengers and to limit the standing room to narrow aisles and at the same time to form a frame work strongly braced and consequently of light construction.

As is best shown in Fig. 3 the carrying frame work is substantially a cross of four arms 10, 11, 12 and 13 braced by, and the upper arm 10 supported by, the rods 14 which rest on the arm 13 and are placed at

regular intervals along the inside of the lower part of the car body. This construction when made up of a number of these frames united by longitudinal rods 15 and braced by angle pieces 16 if necessary, forms a substantial metal structure for a car body to carry heavy loads in the shape of seated passengers, the number of such cross shaped frames depending upon the length of the vehicle and the load to be carried.

The seats are arranged in lower tiers 17 and upper tiers 18, the seats 17 having an aisle between them and the opposite occupants will face each other. The upper seats 18 are divided by a common back 18' and face outward, and the occupants have an unobstructed view through the windows 19, adapting the vehicle as an observation car and making no provision for standing passengers in the upper part of the car. In the lower floor the aisle between the seats is wide and the rods 14 afford ample means for the standing passenger to secure himself in an upright position as the car moves.

The vehicle may be provided, especially in winter, with the top 20 of any desired light construction and secured to the frame of the body, and when the top is dispensed with in temperate weather the open air seats may prove more desirable than those within the enclosure below.

Wheels 21 of any desired type and size are provided and supported on axles 22 carried in the recess 23 of the lower floor of the vehicle and which necessitates the platform 24' at the entrance of the lower floor but which forms one of the steps in the flight to the upper tier of seats.

The upper seats are reached by the winding stairs 24 shown in Fig. 2 as starting within the aisle of the lower tier of seats and by means of low risers making a half turn and landing in the upper aisles at the sides of the car, a suitable railing being provided for each flight and posts 25 limit the door opening on the lower floor.

The ventilators 26 are not an absolute necessity but under ordinary circumstances may be found desirable.

In the modified form shown in Fig. 4 the parts forming the frame are substantially the same but it resembles the letter H with the lower rows 27 of seats back to each other and the aisles 28 along the outer walls 29. The upper seats 30 are against the walls 29.

and the passengers are face to face while bracing and supporting rods 31 extend from the floor to the roof, carrying the floor 32 of the aisle 33 and affording assistance to 5 the standing passengers therein.

In the preferred form of construction recesses are formed under the arms 11 and 12 of the cross and the seats thereon the entire 10 length of the vehicle, and in the same are located the springs, wheels and motors. The former are located on bars 34 supported at each end by the axles 22, and on the steering knuckles 35, each carrying on its pivot a 15 motor 36 adapted to rotate the wheel 21, the wheels are journaled.

The modified form of vehicle in Fig. 4 does not permit of this construction however so that its running gear may be of the usual type.

20 A modified form of stairway is shown in Figs. 5 and 6 where with high risers the flights start on the platform 24' and with a quarter turn land at the front ends of the upper aisles. In these views it will be also 25 observed that at the rear of the lower floor of the vehicle is a platform 37 under which may be located tanks or storage batteries, while motors for light, compressed air or driving power may be located under the rear 30 seats on the same floor, although the motors on the knuckles 35 are to be preferred.

The motorman's cab 38 is located at one side of the platform and within same is the steering and control means for the entire vehicle; while at the other side of the platform is the only entrance and at this

point may be located the conductor or the man to collect the fares.

When the length and requirements demand it, bracing is resorted to in addition 40 to the rods 14 and the bars 34 and all of this metal work is of light construction as possible for the strength required.

It is obvious that other modifications or arrangements of the parts may be resorted to 45 without departing from the essential features above described or from the scope of the appended claims.

What I claim as new is:

1. In a vehicle, the combination of a series 50 of upright frames spaced at intervals and having central lower depressions for an aisle and lower outside recesses, axles passing through the depressions, steering knuckles at the end of the axles, motors on the steering 55 knuckles, wheels, elevated portions to the upper sides of the frames and constituting head room for the aisles, and seats on the elevated portions.

2. In a vehicle, the combination of a series 60 of frames having upper extensions and lower depressions to form an aisle, vertical braces connecting the extension and the depression, longitudinal connecting bars, axles passing 65 through the depressions, wheels at the ends of the axles and in the recesses adjacent to the depressions, and motors for the wheels and supported by the ends of the axles.

Signed at New York, in the county of New York, and State of New York, this 31st day 70 of December, A. D. 1917.

MORTIMER S. BROWN.
